US0D1084075S

(12) **United States Design Patent** (10) **Patent No.:** **US D1,084,075 S**
(45) **Date of Patent:** **** Jul. 15, 2025**

(54) **MODEL VEHICLE TRANSMISSION HOUSING**

(71) Applicant: **TRAXXAS, L.P.**, McKinney, TX (US)

(72) Inventors: **Adam Cole Ewing**, McKinney, TX (US); **Otto Karl Allmendinger**, Rowlett, TX (US); **Kent Poteet**, Lucas, TX (US); **Ross Martin**, Roanoke, TX (US); **Trent Collins**, McKinney, TX (US); **Caleb Hix**, McKinney, TX (US)

(73) Assignee: **TRAXXAS, L.P.**, McKinney, TX (US)

(**) Term: **15 Years**

(21) Appl. No.: **29/852,488**

(22) Filed: **Sep. 7, 2022**

(51) **LOC (15) Cl.** **21-01**

(52) **U.S. Cl.**

USPC **D21/561**

(58) **Field of Classification Search**

USPC D15/5, 9.1, 79, 89, 145, 146, 147, 148, D15/149, 150, 199; D21/561, 562

(57) **CLAIM**

The ornamental design for a model vehicle transmission housing as shown and described.

DESCRIPTION

FIG. 1 is an upper, left, front perspective view of a model vehicle transmission housing showing our new design; FIG. 2 is a front elevation view thereof; FIG. 3 is a rear elevation view thereof; FIG. 4 is a right side elevation view thereof; FIG. 5 is a left side elevation view thereof; FIG. 6 is an upper plan view thereof; FIG. 7 is a lower plan view thereof; FIG. 8 is an upper, right, rear perspective view thereof; FIG. 9 is a lower, right, rear perspective view thereof; and, FIG. 10 is a lower, left, front perspective view of the model vehicle transmission housing. In the drawings, the broken lines illustrate portions of the model vehicle transmission housing that form no part of the claimed design.

1 Claim, 7 Drawing Sheets
